GRATE.

1,236,023.

Specification of Letters Patent.

Patented Aug. 7, 1917.

Application filed November 27, 1911, Serial No. 662,682. Renewed January 15, 1917. Serial No. 142,559.

To all whom it may concern:

Be it known that I, GEORGE LESLIE WALKER, a citizen of the United States, residing at Pueblo, in the county of Pueblo, 5 and State of Colorado, have invented a certain new and useful Improvement in Grates, of which the following is a full, clear, and exact description.

This invention is an improvement in 10 grates designed for use in furnaces where coal is burned either for steam generation, or for the utilization in any other manner of the heat liberated by such combustion. The principal objects of my invention are to provide a grate on which the fuel will be more 15 thoroughly and efficiently acted upon by the air; to so design the grate structure that the air will be heated prior to coming into contact with the fuel; to provide means 20 through which the amount of air admitted to the fire may be regulated by manipulation of the grate; and, withal, to so design the grate that it shall be simple and economical to construct, shall be capable of manufacture 25 by casting, and shall not be easily injured or burned out in use.

It is a well recognized fact that if air can 30 be successfully introduced into the fire in sufficient quantities in a lateral direction, as well as vertically, more complete and efficient combustion will be obtained than on the flat type of grate now in use. This is for the reason that the path of the air through the bed of combustible is longer if it be introduced in a horizontal direction, and the 35 opportunity for the oxygen of the air to combine with the oxidizable elements of the fuel is correspondingly greater. I am aware that grates have hitherto been devised with 40 the object of passing air into the fire in a direction other than vertically, but there are certain characteristics, absent in those proposed structures, which a grate must possess before it can successfully meet the requirements 45 of practice—particularly under steam boilers. A practical grate must be simple and cheap to construct, should be easy to mold and cast, and must not have small or intricate parts which will be easily burned 50 out. My grate, further advantages of which will hereinafter appear in the specification, and be pointed out in the appended claims, is adapted to meet all the requirements above

mentioned, and also to accomplish the objects of invention set forth.

In the drawings, Figure 1 is a perspective of a part of a grate constructed according to my invention; Fig. 2 is an end elevation of a pair of grate bars, embodying a modified form of my invention, showing mechanism for operating said bars; Fig. 3 is a perspective of one of the leaves or teeth of which my grate bars may be built up; Fig. 4 is a plan view, showing a portion of two 60 grate bars, constructed according to another 65 modification of my invention; and Fig. 5 is a perspective of a still further modification of the broad idea of my invention.

For the sake of clearness of illustration I have shown my grate bars as built up of a 70 series of leaves, or fingers, A, B, identically alike, but turned in different directions, and mounted on a square shaft, having round ends to serve as trunnions. While I prefer to make the grate of these separate leaves so 75 mounted, and shall describe it in that embodiment in this specification, it will be clearly evident that the entire grate may, if it is so desired, be cast as a unitary structure, without in any way departing from my invention.

In Fig. 3 I have shown in detached view one of the leaves or teeth, which constitute the similar elements A, B, of my grate bar. These elements are shaped somewhat like 85 the letter L—one leg, marked a, being longer than the leg a¹ and ending in a heel b. The heel has a square opening 4^a therein, thus adapting the leaf to fit on the square shaft 4, as clearly shown in Figs. 1 and 2. In 90 the preferred form the leaf is flattened at 9 to provide a substantially horizontal bed for a portion of the fuel; but I may omit this feature, and continue the planes of the tops of the legs a, a¹, until they meet without departing from my broad invention. I 95 also prefer to bevel the top 2 of the heel b, as shown in Fig. 3.

In the form of grate shown in Fig. 1, the leaves are mounted on square shaft 4 (which has rounded ends to serve as trunnions) and are separated from each other by liners 1. In this form the leaves A, B, are all mounted so that the L is inverted, but alternating on opposite sides of the shaft 4, so that the teeth are in staggered relation. The shafts 4

are so close together that the leaves of adjacent bars intermesh, resulting in a grate having ridges, which are termed pyramids, having open sides and tops, and extending up 5 into the bed of the fire between each pair of shafts.

In the modification shown in Fig. 2, the teeth A on one bar are inverted, and the teeth B are mounted in upright position, 10 this order being reversed on the next adjacent bar, thus making a structure having alternate pyramids above and below the axial shafts 4, the pyramids above the shafts extending into the fire and those below the 15 shafts inclosing a portion of the fire; each form, however, furnishing free access of air to the fuel from the sides.

The form shown in Fig. 5 is illustrative of a type in which the angle 9^a (Fig. 3) is 20 eliminated, and a leaf curved in an arc of a circle is substituted for that shaped as in Fig. 3. I have shown in this figure the curvature as circular, but it will be clear that teeth of other uniform curvature (as 25 for instance that of the catenary) may be substituted therefor without departing from my invention.

It will be noted that in each of the modifications there is a transverse plane, which 30 is vertical when the bars are in normal position, with respect to which the legs a, a¹, are symmetrically disposed—aside from the asymmetry resulting from one of the legs being longer than the other. This is the 35 plane in a uniformly curved tooth where the "sign" of the curvature changes with reference to the horizontal; and in a tooth having a flattened portion 9 it is the central transverse plane through this flattened portion. This applies to the teeth whether in 40 upright or inverted position and I have employed the term "crown" to refer to this plane.

The contour of leaves or teeth shown in 45 Fig. 4 is adapted to be used with any of the modifications of Figs. 1, 2, or 5. In this figure the leaves are shown as having a thickened portion T around the crown. The function of this portion is to impede the vertical passage of air through the horizontal portion of the grate bar, thus forcing a greater percentage of air to pass through 50 the sides of the pyramid and adding to the cross aeration of the fire.

55 Depending from the shafts 4, and formed as parts either of a liner 1, or of one of the leaves A, B, are arms 5, connected at their bottoms to a link 6 by pins 7, held in position by cotters 8. The link 6 is attached 60 to a lever 10 by pin and cotter connection 11, 12. The lever 10 is fulcrumed at 14, where is also mounted the segment 15, provided with notches 16, 17, 17^a, 18, and 18^a.

A dog 19, pressed downwardly by the 65 compression spring 20, and guided by the

bracket 22, is normally in position to engage one of the notches in the segment. The dog 19 is connected at 21 to an actuating link 23, manipulated by a bell crank 24; by which the dog may be disengaged from the 70 notches by gripping the bell crank 24. The lever 10 may then be shifted to rock the grate bars and move the leaves A, B, with relation to one another. This will produce a clearing action by which any clinker tending 75 to form will be forced away from the grate. If the lever 10 be not returned to the intermediate position in which it is shown in Fig. 2, but be left in one of the side notches, the leaves will not be in as 80 close relation, and the amount of air admitted to the fire will be increased. It will thus be seen that the draft on the grate may be regulated at will by manipulation of the grate itself. It is very desirable to have 85 some means of adjusting the amount of air to be admitted to the grate to meet varying atmospheric conditions, or where, as frequently happens, the steaming qualities of an installation do not, for some reason, meet 90 the requirements.

The manner of operation of my device is as follows, reference being had in particular to Fig. 1. The air entering from below is heated in the pockets formed by the curvature of the leaves or teeth. It then passes between the leaves into the fire. On account of the peculiar shape of the grate, the path of a large percentage of the air through the fuel is in an inclined direction, more or less 100 approximating the horizontal, and as the distance between adjacent pyramids is comparatively short, the mass of fuel lying there between is thoroughly exposed to the action of the blast. Some air will pass into the fire vertically (at the highest point 9 of the grate) but as the bed of fuel here is comparatively thin complete oxidation will take place also 105 at that point. If it is desirable to still further reduce the percentage of air passing 110 vertically through the fire, resort may be had to the expedient illustrated in Fig. 4, where the spaces between adjacent teeth at the crown of the grate are decreased by thickening the teeth at that point. Cross 115 aeration of the fire at its lowest point (that is over the spine or web) is assured by air passing under the lower points of the legs a¹, and the distance of these points from the spine is proportioned in such manner 120 that sufficient air is admitted for the complete combustion of the fuel lying on the spine.

The form shown in Fig. 2 also provides cross aeration at practically all points of the 125 fire, and this form is adapted to cases where a deeper bed of fuel is desired—for instance, in case lump coal is being burned.

In any form, if it is desired to admit more air, this can easily be effected (as stated 130

above) by throwing the grate bars with relation to one another. By throwing the lever 10 to the right all bars are rotated in a clock-wise direction, and adjacent leaves 5 in opposite direction. If the leaves do not lie in the same plane they offer less resistance to the passage of air, and this resistance may be varied at will by turning the bars a greater or less distance.

10. In the claims which form a part of this specification I have referred to the leaves or teeth of my grate as being L-shaped, but this should not be interpreted as meaning that the legs α and α' must be at right angles to one another. On the contrary I intend this term to include all possibilities of shape from the slightest angularity which will give a sufficient rise to the grate to form a pyramid such as will give side draft, as 15 described; to the form where the angle between the legs is very acute. I also intend this term to include the arc shaped form shown in Fig. 5 (which is the limit of the L) and all other curved teeth, such as sickle shaped, 20 where the curvature of the teeth is the same throughout. I further intend this term to cover the tri-lateral shaped teeth, similar to that illustrated in Fig. 3, but where the flattened portions 9, 9^a, are elongated. The 25 claims accompanying this application are to be interpreted in view of the meaning given to the expression "L-shaped" by this paragraph.

Having thus described my invention, what 30 I claim and desire to secure by Letters Patent is:

1. In a grate, a plurality of grate bars, each grate bar having a spine and a plurality of L-shaped teeth projecting from said 35 spine, the teeth of each grate bar so intermeshing with those of the next adjacent grate bar that the outer end of each tooth extends beyond the crown of the adjacent tooth on the adjacent grate bar.

40 2. In a grate, a plurality of grate bars, each grate bar having a spine and a plurality of L-shaped teeth projecting from said spine out of the plane of the top thereof, the teeth of each grate bar so intermeshing with those of the next adjacent grate bar that the outer end of each tooth extends beyond the crown of the adjacent tooth on the adjacent grate bar.

45 3. In a grate, a plurality of grate bars, each grate bar having a spine and a plurality of L-shaped teeth projecting from said spine, the longer leg of the L being adjacent the spine and the teeth of each grate bar so intermeshing with those of the next 50 adjacent grate bar that the outer end of each tooth extends beyond the crown of the adjacent tooth on the adjacent grate bar.

55 4. In a grate, a plurality of grate bars, each grate bar having a spine and a plurality of L-shaped teeth projecting from said spine, the longer leg of the L being adjacent the spine and the teeth of each grate bar so intermeshing with those of the next 60 adjacent grate bar that the outer end of each tooth extends beyond the crown of the adjacent tooth on the adjacent grate bar.

5. In a grate, a plurality of grate bars, each grate bar having a spine and a plurality of L-shaped teeth projecting from said 65

spine out of the plane of the top thereof, the longer leg of the L being adjacent the spine and the teeth of each grate bar so intermeshing with those of the next adjacent grate bar that the outer end of each tooth extends beyond the crown of the adjacent tooth on the adjacent grate bar. 70

6. In a grate, a plurality of grate bars, each grate bar having a spine and a plurality of L-shaped teeth projecting from said spine, the teeth of each grate bar so intermeshing with those of the next adjacent grate bar that their respective crowns lie in substantially the same vertical plane, thus forming a pyramid out of the plane of the 75 grate which pyramid has lateral and crown openings between adjacent teeth. 80

7. In a grate, a plurality of grate bars, each grate bar having a spine and a plurality of downwardly turned L-shaped teeth projecting upward from the plane of the top of said spine, the teeth of each grate bar so intermeshing with those of the next adjacent grate bar that their respective crowns lie in substantially the same vertical plane, thus forming a pyramid above the plane of the top of the spine which has lateral and 85 top openings between adjacent teeth. 90

8. In a grate, a plurality of grate bars, each grate bar having a spine and a plurality of L-shaped teeth projecting from said spine, the longer leg of the L being adjacent the spine, the teeth of each grate bar so intermeshing with those of the next adjacent grate bar that their respective crowns lie in substantially the same vertical plane, thus 95 forming a pyramid above the plane of the top of the spine which has lateral and top openings between adjacent teeth. 100

9. In a grate, a plurality of grate bars, each grate bar having a spine and a plurality of downwardly turned L-shaped teeth projecting upward from the plane of the top of said spine, the longer leg of the L being adjacent the spine and the teeth of each grate bar so intermeshing with those of the next adjacent grate bar that their respective crowns lie in substantially the same vertical plane, thus forming a pyramid above the plane of the top of the spine which 105 has lateral and top openings between adjacent teeth. 110

10. In a grate a series of grate bars, bent teeth on said grate bars, said teeth intermeshing with the teeth on adjacent grate 115 bars to form a pyramid having lateral and crown openings therein, said pyramid extending out of the plane of the top of the grate bar spines. 120

11. In a grate a series of grate bars, each 125 grate bar having a spine and L-shaped teeth projecting from the opposite sides thereof in staggered relation, the grate bars being so placed that the teeth on adjacent grate bars intermesh and the teeth being so shaped and 130

proportioned that there is formed intermediate each pair of spines a single pyramid having lateral and crown openings.

11. In a grate, a plurality of grate bars 5 having bent teeth, the inner portion of each tooth making an angle with the horizontal and the outer portion of each tooth making a substantially equal angle with the horizontal but in an opposite direction, the grate bars being so relatively placed that the teeth of each grate bar so intermesh with those of the next adjacent bar that the outer end of each tooth extends beyond the crown of the adjacent tooth on the adjacent grate 10 bar.

12. In a grate, a plurality of grate bars having bent teeth, the inner portion of each tooth making an angle with the horizontal and the outer portion of each tooth making a substantially equal angle with the horizontal 20 but in an opposite direction and the outer portion of the teeth being shorter than the inner, the grate bars being so relatively placed that the teeth of each grate bar so intermesh with those of the next adjacent bar that the outer end of each tooth extends beyond the crown of the adjacent tooth on the adjacent grate bar.

13. In a grate, a series of grate bars, each 30 grate bar being composed of a spine and a plurality of L-shaped teeth projecting therefrom, the grate bars being so spaced that the teeth on adjacent grate bars intermesh and the teeth being so shaped and proportioned as to coöperate in forming, intermediate the axes of each pair of adjacent grate bars, a pyramid having lateral and crown openings, a single tooth serving to form a portion of opposite side walls of each pyramid.

14. In a grate, a plurality of grate bars, each grate bar having a spine and a plurality of L-shaped teeth, having a horizontally thickened portion adjacent the angle 45 of said L, projecting from said spine, the teeth of each grate bar intermeshing with those of the next adjacent grate bar with the thickened portions of adjacent teeth in substantial alinement.

15. In a grate, a plurality of grate bars, each grate bar having a spine and a plurality of L-shaped teeth, having a horizontally thickened portion adjacent the angle of said L, projecting from said spine, the 55 longer leg of the L being adjacent the spine, and the teeth of each grate bar intermeshing with those of the next adjacent grate bar with the thickened portions of adjacent teeth in substantial alinement.

16. In a grate, a plurality of grate bars, each grate bar having a spine and a plurality of L-shaped teeth projecting from said spine, said teeth having a horizontally thickened portion adjacent the angle of said 65 L, the teeth of each grate bar intermeshing

with those of the next adjacent grate bar and in substantial parallelism therewith, thus forming a pyramid above the plane of the top of the spine which has lateral and crown openings between adjacent teeth, the 70 crown openings being narrower than the lateral openings.

17. In a grate, a plurality of grate bars, each grate bar having a spine and a plurality of L-shaped teeth projecting from 75 said spine, said teeth having a horizontally thickened portion adjacent the angle of said L, the longer leg of the L being adjacent the spine, the teeth of each grate bar intermeshing with those of the next adjacent 80 grate bar and being in substantial parallelism therewith, thus forming a pyramid above the plane of the top of the spine which has lateral and crown openings between adjacent teeth, the crown openings 85 being narrower than the lateral openings.

18. In a grate, a series of grate bars having bent teeth provided with a horizontally thickened portion adjacent the crown of said teeth, the grate teeth intermeshing with the teeth on adjacent grate bars to form a pyramid having lateral and crown openings therein, the crown openings being more restricted than the lateral openings, and said pyramid extending out of the plane of the 95 top of the grate bar spines.

19. In a grate, a series of grate bars, each grate bar having a spine and L-shaped teeth projecting from the opposite sides thereof in staggered relation, the grate bars being 100 so placed that the teeth on adjacent bars intermesh and the teeth being so shaped and proportioned that there is formed intermediate each pair of spines a pyramid having lateral and crown openings therein, the 105 crown openings being more restricted than the lateral openings.

20. In a grate, a plurality of grate bars having bent intermeshing teeth, the inner portion of said teeth making an angle with the horizontal and the outer portion of said teeth making an approximately equal angle with the horizontal but in an opposite direction, the teeth being wider at the junction between the inner and outer portions 110 than in other parts.

21. In a grate, a plurality of grate bars having bent intermeshing teeth, the inner portion of said teeth making an angle with the horizontal and the outer portion of said teeth making an approximately equal angle with the horizontal but in an opposite direction, the outer portion of the teeth being shorter than the inner and the teeth being wider at the junction between the inner 115 and outer portions than in other parts.

22. In a grate, a plurality of grate bars having bent teeth and the teeth of each grate bar so intermeshing with those of the next adjacent grate bar that their 120 125 130 135

tive crowns lie in substantially the same vertical plane, and means for shifting the angular relation of the teeth of adjacent grate bars to vary the amount of air passing through the grate.

23. In a grate, a series of grate bars, bent teeth on said grate bars, said teeth intermeshing with the teeth on adjacent grate bars to form a pyramid having lateral and 10 crown openings therein, and means for shifting the angular relation of the teeth of adjacent grate bars to vary the amount of air passing through the grate.

24. In a grate, a plurality of grate bars, 15 each grate bar having a spine and a plurality of L-shaped teeth projecting from said spine, the teeth of each grate bar so intermeshing with those of the next adjacent

grate bar that the outer end of each tooth extends beyond the crown of the adjacent 20 tooth on the adjacent grate bar, an arm depending from each spine, a link connecting said arms and joined at its outer end to a lever, in combination with means for retaining the lever in varying angular position, whereby the grate bars may be rocked to vary the relative position of the grate bar teeth and the amount of air admitted to the fire.

25] In testimony whereof I hereunto affix my 30] signature in the presence of two witnesses.

GEORGE LESLIE WALKER.
